(57) **CLAIM**

The ornamental design for a sausage, as shown and described.

DESCRIPTION

The patent or application file contains at least one drawing executed in color. Copies of this patent or patent application publication with color drawing(s) will be provided by the Office upon request and payment of the necessary fee.

1. Sausage

1.1 : Perspective

1.2 : Front

1.3 : Right

1.4 : Left

1.5: Top

1.6: Bottom

1.7: Back

The matter displayed in reproductions 1.1 to 1.7 in light red color, representing a surface of the sausage, is not part of the claimed design.

(Continued)

The claimed subject of the application is a ring shaped sausage with irregular edges.

**1 Claim, 7 Drawing Sheets
(7 of 7 Drawing Sheet(s) Filed in Color)**
